UNITED STATES PATENT OFFICE.

SAMUEL SHAFER, JR., OF MILWAUKEE, WISCONSIN, ASSIGNOR TO CHAIN BELT COMPANY, OF MILWAUKEE, WISCONSIN, A CORPORATION OF WISCONSIN.

POWER-DRIVEN CHUTE-OPERATING MECHANISM.

1,415,411.

Specification of Letters Patent. Patented May 9, 1922.

Application filed January 20, 1921. Serial No. 438,801.

To all whom it may concern:

Be it known that I, SAMUEL SHAFER, Jr., a citizen of the United States, residing at Milwaukee, in the county of Milwaukee and 5 State of Wisconsin, have invented certain new and useful Improvements in Power-Driven Chute-Operating Mechanism, of which the following is a specification.

My invention relates to a motor driven, as 10 distinguished from a manually operated, mechanism for operating a chute through which material is passed. An example of this type of apparatus is illustrated in U. S. Letters Patent #1,230,731 to C. W. Levalley.

15 The invention has for its object to simplify, improve, and make compact, mechanism of this kind.

In the accompanying drawings—

Figure 1 is a side elevation of apparatus 20 embodying my invention devised for operating the discharge chute of a concrete mixing machine.

Figure 2 is a rear elevation of the same apparatus.

25 In the accompanying drawings A designates a rotated drum of a concrete mixing machine and B the discharge chute thereof. This chute is similar to that represented in U. S. Letters Patent #1,243,614 to C. W. 30 Levalley, and consists of an inner section b and an outer section b', these sections being united by pivotal or hinge connections d. The invention is applicable, however, to other forms of chutes, whether used for delivering material from or to a receptacle, of 35 which that designated A in the accompanying drawings is but a type. The chute is supported by arms fixed to a shaft 14 that extends across the machine in rear of the 40 drum, and preferably above the discharge opening a therein. 2 designates a power shaft, which may be the shaft from which the drum is driven, and which, therefore, turns whenever the machine is in operation.

45 Secured upon this shaft is a spur gear wheel 1 that meshes with a pinion 3 fastened on to the driven countershaft, 4. 7 designates a worm, preferably loose upon the shaft 4, but adapted to be connected therewith 50 through a clutch the shifting member of which is designated 5, and meshing with the worm wheel 8 mounted on a short shaft 9. This member 5 is keyed to the shaft 4 and is movable, longitudinally, thereon so that 55 the countershaft 4 and the parts which it

drives may be connected with the source of power at the will of the operator. The clutch member 5 is shifted through the instrumentality of a manually controlled lever 6 and yoke or shifting fork 18, carried by 60 a shaft 17.

The shaft 9 also carries a cam, consisting of a disk 10, in diametrically opposite portions of the periphery of which are formed the recesses 22, 22,—and a relatively short 65 crank arm 11. The latter is connected by a link 12 with a longer crank arm 13 on the shaft 14 that carries the chute B. Link 12 is adjustable in order to control the position of the chute. 70

16 designates an arm extending from the shaft 17 and carrying at its outer end a roller 19 adapted to engage with the periphery of the cam 10. The relation of the arm 16 to the clutch shifting fork 18 is such 75 that when the roller 19 occupies one of the recesses 22 the movable clutch is shifted to disconnect the chute operating mechanism from the source of power, but when such roller engages with the high peripheral portions of the cam between the recesses, the clutch is moved to connect the worm 7 with the source of power. A spring 20 interposed between the fork 18 and some fixed support tends to hold the roller in engagement with 80 the periphery of the cam 10. The mechanism described, except the levers and pinion 3, are mounted in and enclosed by a housing 21 which is supported by the framework of 85 the machine to which the apparatus is applied. 90

In the operation of a concrete mixing machine the chute B is maintained at rest for certain periods of time in either one or the other of two positions. One of them, represented in full lines in Fig. 1, is that occupied when material is being discharged from the mixing drum; while the other, represented in dotted lines in the same view, is the position occupied while the chute is inactive, 95 and during the time the batch of concrete is being mixed but not discharged. In stating the operation of the apparatus it will be assumed that the chute is in the inactive position and that the contents of the drum, 100 having been properly mixed, is to be discharged. The attendant moves the lever 6, or clutch shifter, and connects the chute-moving mechanism with the source of power. 105 This causes the shaft 9 and the parts it car- 110

ries to rotate and the chute to be moved to the full line position in Fig. 1. In shifting the lever 6 as just described the arm 16 is moved so as to carry the roller 19 out of the 5 recess in which it was resting, and, as soon as rotation of this shaft begins, a high portion of the cam 10 comes opposite the roller and the operator may then release the lever, which is held in the position to which it has 10 been moved by the cam until the other recess 22 comes opposite the roller 19 when the spring 20 will shift the clutch shifting fork 18 and cause the roller to drop into the recess 22. These movements disconnect the gear- 15 ing from the power shaft and at the same time lock the shaft 9 against rotation. As has been stated, the crank 11 on the shaft 9 is shorter than the crank 13 on shaft 14, with the result that the rotation of the shaft 20 9 causes an oscillation of the shaft 14 and the chute which it carries. When the chute is to be moved to its outer or inactive position the operator again shifts the lever 6 to connect the shaft 14 with the source of power, 25 whereupon operations, similar to those that have been described, take place, except that the half revolution then given to the shaft 9 causes the chute to be moved from its inner to its outer position.

30 There are several advantages incident to the mechanism that has been described, amongst which may be mentioned its compactness and simplicity, the fact that it may be easily applied to various sizes and types 35 of machines, the fact that a reversing of the rotation of the shaft 9 is not required in order to effect the two movements of the chute; and the fact that safety stops are not required, for if the spring 20 should 40 break or fail to function the chute would merely continue to oscillate until the clutch was thrown by hand.

What I claim is:—

1. A chute, a shaft by which it is supported, a second shaft, connections between these shafts whereby on the rotation of the latter the chute-carrying shaft is oscillated, power transmitting gearing, including a clutch, for driving the said second shaft, a 45 shifter for operating the clutch and a cam arranged to actuate the clutch shifter to automatically disconnect the power at pre-

determined positions of the chute-carrying shaft.

2. A chute, a shaft by which it is supported, a second shaft, connections between these shafts whereby on the rotation of the latter the chute-carrying shaft is oscillated, power transmitting gearing, including a clutch, for driving the said second shaft, a 55 shifter for operating the clutch and a cam arranged to actuate the clutch shifter to automatically disconnect the power at each oscillation of the chute-carrying shaft.

3. A chute, a shaft by which it is supported, a second shaft, connections between such shafts whereby on the rotation of the latter the chute-carrying shaft is oscillated, power transmitting gearing, including a clutch for driving the second shaft, a cam 60 and a manually controlled clutch shifter having an arm actuated by the cam to throw the clutch and disconnect the power at each oscillation of the chute-carrying shaft.

4. A chute, a shaft by which it is supported, a second shaft, power transmitting gearing for driving the second shaft including a counter shaft, a clutch and worm gearing between the countershaft and said second shaft, connections between the said second shaft and the chute-carrying shaft arranged to cause oscillation of the latter when the said second shaft is rotated, a clutch shifter having a manually controlled handle and an arm, a cam with which the arm of the 70 clutch shifter engages, the cam being arranged to actuate the clutch shifter to disconnect power at the completion of each oscillation of the chute-carrying shaft, and a spring for holding the arm in engagement 75 with the cam.

5. A chute, a shaft by which it is supported, power transmitting mechanism for intermittently oscillating the shaft and moving the chute, including a clutch, a lever 80 for shifting the clutch, and a cam for automatically disengaging the clutch and locking the chute in predetermined positions.

6. In an oscillating chute as described in claim 5 the combination therewith of adjustable means for varying the position in which the chute is locked.

SAMUEL SHAFFER, JR.
